UNITED STATES PATENT OFFICE.

WILLIAM W. PLOWMAN, OF JEWELL, KANSAS.

TUG-LOOP.

No. 906,066.

Specification of Letters Patent.

Patented Dec. 8, 1908.

Application filed July 6, 1907. Serial No. 382,494.

To all whom it may concern:

Be it known that I, WILLIAM W. PLOWMAN, a citizen of the United States, residing at Jewell city, in the county of Jewell, State 5 of Kansas, have invented certain new and useful Improvements in Tug-Loops; and I do hereby declare the following to be a full, clear, and exact description of the invention, such as will enable others skilled in the art 10 to which it appertains to make and use the same.

This invention relates to tug loops and is designed for the purpose of holding the ends of long tugs against the short tugs of a harness. Without the use of some such means, the end of the long tug soon becomes curled outwardly and not only presents a very unsightly appearance, but soon becomes considerably worn.

20 The tug loop embodied in my invention is of such construction that it may be applied to any tug now in use and readily removed therefrom or adjusted thereon whenever occasion requires and hence it may be placed 25 upon the market as an article by itself.

In the accompanying drawings, Figure 1 is a front elevation of the loop applied to a harness tug, Fig. 2 is a similar view but in detail and showing the loop removed from 30 the tug, Fig. 3 is a side elevation of the loop showing the same closed, and, Fig. 4 is a similar view but showing the loop open.

As shown in the accompanying drawings the loop is formed in part of a single strand 35 of wire bent at opposite sides of its middle as at 6 to form parallel portions 7 which extend vertically and at right angles to the middle portion of the wire and these portions 7 are bent as at 8 to form forwardly and right angularly extending portions 9, the portions 7 as well as the portions 9 being in parallel relation. The portions 9 are bent as at 10 to form downwardly and right angularly extending portions 11 which, adjacent their 40 lower ends are bent to form portions 12 which extend inwardly toward each other and which have their extreme ends bent downwardly and rearwardly as at 13 in spaced parallel relation with respect to each 45 other.

A U-shaped bail 14 is pivoted at the end of its arms as at 15 to the middle portion of

the loop and pivoted as at 16 between the end portions 13 is a cam finger lever 17 provided in its forward edge with a notch 18 in which 55 the connecting portion of the bail 14 is engaged when the loop is in use.

In using the loop, the bail 14 is swung downwardly and the loop engaged over the short tug and the end of the long tug of the 60 harness the loop then being swung upwardly and engaged in the notch 18 in the cam finger lever 17 this lever being at such time in substantially horizontal position. After such engagement of the connecting portion of the 65 bail in the notch 18, the lever is swung upwardly and the loop is clamped upon the tugs and serves to hold the end of the long tug securely against the short tug. When the cam lever is swung upwardly as stated 70 above, the point of engagement of the bail with the lever is in a plane above the point of pivotal connection of the lever with the loop and consequently the lever is securely held in such position until it is desired to shift or 75 remove the bail when the operation above mentioned is reversed.

The lever arm 17 when in closed position as shown in Fig. 3 is disposed between the side members 11—11 which position locates 80 the notch 18 above the line of the pivot 16 so that when the lever 17 is in closed position the loop 14 will be locked to the frame, and prevent accidental displacement.

What is claimed, is—

1. A device of the class described formed from a single section of wire bent centrally into U shape to form spaced vertical sides and the spaced sides again bent into U shape at right angles to the first mentioned bend 90 and with the terminals thereof extending inwardly, a loop swinging from the section of wire at its first bend, and a catch lever swinging from the inwardly extended ends of the terminals and provided with a recess engaging over the loop.

2. A device of the class described comprising two U shaped portions spaced apart with the terminals at one side connected by a transverse portion and the terminals at the 100 other side extending inwardly and thence bent at right angles to the inwardly turned portions, a loop swinging from the transverse portion, and a catch lever swinging be-

85

95

100

tween the inwardly turned terminals and provided with a notch engaging the loop and with a lever arm extending therefrom, whereby when the lever arm is actuated the 5 catch will draw the two portions of the **U** shaped members toward each other and lock them in that position.

In testimony whereof, I affix my signature, in presence of two witnesses.

WILLIAM W. PLOWMAN.
